UNITED STATES PATENT OFFICE

147,926

DESIGN FOR AN AIGLET BROOCH

Sidney Packales, Great Neck, N. Y.

Application August 15, 1946, Serial No. 132,527

Term of patent 3½ years

(Cl. D45—19)

To all whom it may concern:

Be it known that I, Sidney Packales, a citizen of the United States of America, residing in Great Neck, county of Nassau, and State of New York, have invented a new, original, and ornamental Design for an Aiglet Brooch, of which the following is a specification, reference being had to the accompanying drawing, forming part thereof.

Fig. 1 is a perspective view of an aiglet brooch, showing my new design.

Fig. 2 is an edge view thereof.

Portions of the chain elements are indicated in broken lines for illustrative purposes only.

I claim:

The ornamental design for an aiglet brooch, substantially as shown and described.

SIDNEY PACKALES.
